UNITED STATES PATENT OFFICE.

DANVERS CRAM, OF NEWPORT, MAINE.

FULLING-MILL STOP MOTION.

Application filed April 12, 1926. Serial No. 101,446.

The invention relates to cloth-fulling machines or mills, of the type in which guiding racks for the cloth strips being fulled, are moved by snarls in the strips, and when so moved, are effective to automatically stop the feeding means for the strips. Ordinarily, a single, movably mounted rack, is provided to guide a plurality of cloth strips, and in order that a snarl or the like on one of these strips may stop the machine, the strip necessarily raises the entire weight of the rack. This often causes undue stretching of the strip, as well as causing the feed rolls to burn the material. Then too, breakage of the strip very often occurs.

It is the primary object of the present invention to improve upon machines of the type set forth, by providing independently movable racks or guides for the independent strips of material being fulled. Thus, a snarl or the like on any strip need only lift a comparatively small weight, in order to bring the machine to a standstill.

Fulling machines of the type to which I have referred, are often equipped with a strip engaging roller adapted to be raised by minor snarls of the strips, to bring the machine to a stop. The approximate weight of such a roller is 30 pounds and this weight resting continuously upon the strip, has a number of very undesirable effects. It is therefore another aim of the invention to provide new and improved means to be used in place of the roller, said means extending across the paths of the strips of cloth but being normally at such a position as to be free of contact with said strips. Nevertheless, snarls, knots or the like on the strips can come in contact with the means in question and can consequently operate the same to stop the machine.

With the foregoing in view, the invention resides in the novel subject matter herein-after described and claimed, the description being supplemented by the accompanying drawing.

Figure 1 is a side elevation of a fulling machine improved in accordance with my invention.

Fig. 2 is a top plan view partly broken away and in horizontal section.

Fig. 3 is a longitudinal sectional view on line 3-3 of Fig. 2.

Fig. 4 is a vertical transverse section as indicated by line 4-4 of Fig. 3.

Fig. 5 is a detail side elevation looking in the opposite direction from Fig. 1.

A fulling machine or mill is shown embodying the usual upper and lower feed rolls 6 and 7, boxes 8 and guide roller 9, these parts being disposed as usual in an appropriate housing 10. A clutch 11 is provided for the rolls 7 and the upper rolls 6 are spring pressed by the usual springs 12 and associated parts forming no elements of the present invention. It may also be stated at this point that the boxes 8 are provided with the usual regulating means, portions of which are indicated at 13, these parts 13 also being irrelevant to the present invention.

For controlling the clutch 11, a rock shaft 14 extends along the outer side of the housing 10 and is provided with a clutch shifting fork 15, and also with a lever 16 by means of which the shaft may be turned by hand to either engage or disengage the clutch. Obviously, when the clutch is thrown in, the feed rolls 6 and 7 will be driven to feed the strips of cloth 17 through the machine, whereas when the clutch is thrown out, said machine is brought to a standstill.

Beneath the roller 9, are two strip guiding racks or other adequate guides 18 and 18^a, these guides being carried by independent rock shafts 19 and 19^a respectively, which shafts extend to the exterior of the housing 10. Cranks 20 and 20^a are secured to the outer ends of the shafts 19 and 19^a respectively, said cranks being formed with rod guides 21 and 21^a through which vertical rods 22 and 22^a pass slidably. The upper ends of these rods are pivoted to cranks 23 and 23^a on the ends of a master rock shaft 24 which extends across the housing above the roller 9. Pins 25 and 25^a pass through the rods 22 and 22^a respectively, over the guides 21 and 21^a, and coiled compression springs 26 and 26^a are interposed between said pins and guides. By this construction or some equivalent arrangement, one-way connections are provided between the arms 20-20^a and the rods 22-22^a. Thus, the arm 20 may force upwardly on the rod 22 to turn the shaft 24, without any corresponding movement of the arm 20^a and vice versa. It will thus be seen that if a snarl or the like engages the guide 18, this guide will be swung upwardly, thereby turning the rock shaft 19 and swinging the arm 20 to 110

raise the rod 22, causing the latter to act on the crank 23 and turn the shaft 24. Similarly, if a knot or the like on a strip of the cloth comes in contact with the guide 18^a, the rock shaft 19^a will be turned, causing crank 20^a to force upwardly on rod 22^a, thus causing crank 23^a to turn the rock shaft 24. Provision is made for transmitting motion from this master rock shaft 24, to the clutch throw out shaft 14, so that movement of said master shaft under the lifting motion of either of the guides 18-18^a, will automatically throw out the clutch and stop the machine.

15 In the present showing, the arm 23^a is connected by a vertical rod 27, with an arm 28, the latter being secured to and projecting inwardly from the shaft 14. Thus, each time the shaft 24 is turned by one or the other of the guides 18-18^a rod 27 is lifted, causing the arm 28 to turn the shaft 14, thereby throwing the clutch 11 out. For a purpose to appear hereinafter, certain details are preferably used in connection with the upper and lower ends of the rod 27. The upper end of this rod is connected by a universal joint or the like 29 with the arm 23^a, while the lower portion of said rod is receivable in either of a pair of hooks 30 on the arm 28, said rod being provided with a shoulder 31 under this arm. It is the engagement of this shoulder with the arm, upon lifting of the rod 27, which causes said arm to swing upwardly, thereby turning the shaft 14. The hooks 30, it will be observed, are different distances from the shaft 14. Thus, when the rod is engaged with one, the turning movement imparted to said shaft 14, will be greater than when the rod is engaged with the other. The detachable connection between the rod and arm, afforded by these hooks, also possesses another advantage which will be hereinafter fully explained.

45 Very often, minor knots or snarls on the strips 17, pass through the guides 18-18^a without actuating the stop motion for the machine. Auxiliary means are hence provided to be encountered by such minor imperfections, to bring the machine to a standstill. In the present embodiment of the invention, the shaft 24 is provided with laterally projecting arms 32 carrying a curved shoe 33 substantially arcuate in cross section and which extends transversely of the paths of the strips 17 but is normally supported out of contact with said strips, due to the provision of an adjustable stop 34, upon which the arm 23 of the rock shaft 24, normally rests, as shown in Figs. 4 and 5. Thus, while there is no dragging of the shoe 33 upon the strips 17, any snarl or the like which passes through the guide 18 or 18^a, will engage and lift said shoe, causing rocking of the shaft 24 and pulling of the rod 27

to turn the shaft 14 and disengage the clutch 11. The shoe 33 being of shell-like structure and made of comparatively thin material is of trivial weight compared to the weight of a roller performing a similar function and heretofore commonly used and hence is freely swingable. Hence, less strain is placed upon any strip of cloth which must necessarily raise said shoe. At this point, attention may also be directed to the fact that when a knot or the like on any strip engages the guide 18 or 18^a, the strip must only raise the guide which it engages, so that here again, the weight necessarily raised by the strip, is considerably less than that which must be raised by fulling machines having the common stop motions.

When initially engaging the strips 17 with the machine, it is advisable to support the shoe 33 in an elevated position. This can be done by disengaging the rod 27 from the arm 28 and pushing upwardly upon said rod, thus causing the crank 23^a to turn the rock shaft 24, which carries said shoe 33. The rod 27 may then be supported temporarily upon an appropriate ledge 35, projecting from the housing 10, this ledge being shown in Figs. 1, 2 and 4.

In actual practice, excellent results have been obtained from the general construction herein disclosed. Therefore, such construction is preferably followed. However, within the scope of the invention as claimed, variations may of course be made.

I claim:

1. In a cloth-handling machine, cloth-feeding means having a clutch, a rock shaft for disengaging said clutch, an arm secured to and projecting laterally from said rock shaft, a master rock shaft transverse to the cloth path and having a lateral shoe adapted to be engaged by a snarl to turn said master rock shaft, a crank on said master rock shaft, a rod connecting said crank and said arm and detachably connected with the latter, and means for holding said rod in an abnormal position when disconnected from said arm, said shoe being then spaced from the cloth path.

2. In a cloth-fulling machine, cloth-feeding means, guides for a plurality of cloth strips, means mounting said guides for independent movement, a rock shaft spaced from said guides and disposed transverse to the paths of the cloth strips, one-way operating connections between said guides and said rock shafts permitting movement of any one of said guides to turn said rock shaft, means connected with said rock shaft for stopping the feeding means when said shaft is turned, and laterally projecting strip-engaging means on said rock shaft adapted to be engaged by a snarl to turn said shaft in the same direction in which it is turned by any of said guides.

3. In a cloth-fulling machine, cloth-feeding means, guides for a plurality of cloth strips, means mounting said guides for independent movement, permitting movement 5 of any one guide by a snarl of the cloth strip guided thereby, a rock shaft spaced from said guides, one-way operating connections between said guides and said rock shaft permitting movement of any one of 10 said guides to turn said rock shaft, means connected with said rock shaft for stopping said feeding means when the rock shaft is turned, said rock shaft being transverse to the paths of the cloth strips and having laterally projecting strip-engaging means 15 adapted when engaged by a snarl to turn said rock shaft in the direction in which it is turned by any of the guides, and stop means limiting the turning of the rock shaft 20 in one direction to prevent said strip-engaging means from dragging on the cloth under normal circumstances.
4. In a cloth-fulling machine, cloth-feeding means, guides for a plurality of cloth 25 strips, independent axially aligned rock

shafts to which said guides are secured respectively, one set of cranks independent of said guides and secured one to each of said rock shafts, a master rock shaft spaced from and parallel with said independent 30 rock shafts, a second set of cranks secured to said master rock shaft and equal in number to the cranks of said one set, rods extending directly from the cranks of said one set to the cranks of said second set, direct pivotal connections between said rods 35 and the cranks of one of said sets, connecting means between said rods and the cranks of the other set forming one way driving connections between the latter and said rods 40 and permitting turning of the master rock shaft by turning of any of the independent rock shafts, and stopping means for the aforesaid feeding means operatively connected with said master rock shaft and actuated by turning thereof. 45

In testimony whereof I have hereunto affixed my signature.

DANVERS CRAM.
